UNITED STATES PATENT OFFICE.

LERoy BAUMGARTL, OF CHICAGO, ILLINOIS, ASSIGNOR TO FEDERAL CEMENT TILE COMPANY, OF CHICAGO, ILLINOIS, A CORPORATION OF ILLINOIS.

SKYLIGHT AND ROOFING CONSTRUCTION.

Application filed July 2, 1925. Serial No. 41,090.

To all whom it may concern:

Be it known that I, LEROY BAUMGARTL, a citizen of the United States of America, and a resident of Chicago, county of Cook, and 5 State of Illinois, have invented a new and useful Improvement in Skylight and Roofing Constructions, of which the following is a specification.

This invention relates to roofing and skylight construction of the general character referred to in my Patents Nos. 1,195,643 and 1,417,487; to the structure and manner of connecting preformed cementitious panel units or tiles; and to methods and means 10 for mounting glass or window panes, especially in skylights, and more particularly to such devices of moisture shedding character in which the frame is made of cementitious material, such as concrete or the like.

Heretofore window panes have been set in 15 concrete frames in various ways, but so far as I am aware no means have heretofore been devised wholly avoiding certain serious defects, chief of which have been leakage of rain and cracking of the glass. Condensation of moisture and consequent dripping of water has also been the source of much inconvenience and trouble, as by damaging goods and materials located under skylights.

Defective joints for abutting and overlapping panels are a source of trouble. I seek 20 to overcome all of these difficulties.

The main objects of the invention are to provide an improved form and arrangement of preformed roof panels and means for connecting and sealing the same in a weather-proof manner; to provide an improved construction for skylight panels and methods and means for securing panes of glass therein respectively in a water-tight manner, and adapted to accommodate maximum relative expansion and contraction of the glass and frame; and to provide improved and more effective means for eliminating the moisture of condensation from the inner side of the panels when assembled in a roof structure.

An illustrative embodiment of this invention is shown by the accompanying drawings, in which:—

Fig. 1 is a vertical cross section through a roof structure, on the line 1—1 of Fig. 2.

Fig. 2 is a fragmentary top view of the roof shown in Fig. 1.

Fig. 3 is an isometric view of a skylight 55 panel comprising a preformed cementitious frame having a glass panel set therein.

Fig. 4 is an isometric view of a solid panel adapted for interchangeability relative to the panel of Fig. 3.

Fig. 5 is a vertical section on the line 5—5 of Fig. 2.

Fig. 6 is a vertical section on the line 6—6 of Fig. 2.

Fig. 7 is a section on the line 7—7 of 65 Fig. 2.

Fig. 8 is a section on the line 8—8 of Fig. 2.

Fig. 9 is a section on the line 9—9 of 70 Fig. 2.

Fig. 10 is a magnified section on the line 10—10 of Fig. 5 to show the yielding anti-friction lining of the weep hole or moisture outlet.

In the construction shown in the drawings, sufficient of the building frame 1 is shown to illustrate how the panels are applied. In this instance the roof frame includes a plurality of horizontally disposed bars or carlines 2, on which the panels 3 80 and 4 are mounted, being laid thereon and held in place mainly or wholly by gravity.

The solid panels 3 and the skylight panels 4 may be arranged in any manner desired, but for illustrative purposes I have shown 85 merely a middle horizontal row of skylight panels 4, with top and bottom rows of solid panels 3 above and below the panels 4.

Successive courses of panels are arranged in mutually staggered relation, beginning 90 at the bottom, so as to break joints and produce the best form of roof, each successive course at its lower edge overlapping the upper edge of the preceding course, substantially as shown in Fig. 2. Referring now to 95 the panels shown in Figs. 3 and 4, it is to be observed that each panel at its upper edge is provided with a downwardly turned flange 5 to hook over the adjacent bar 2 for supporting the panel against sliding down- 100

wardly toward the eaves, the lower edge of the panel being substantially plane on its under side to overlap and rest upon the next lower panel and bar 2, on which it rests. 5 The vertical joints between adjacent panels are illustrated by Figs. 7, 8 and 9. Here the two adjacent skylight panels 4 abut substantially together, with a slight clearance at 6 to accommodate expansion. The upper 10 sides of the panel edges project upwardly somewhat to provide longitudinal flanges 7, which are suitably beveled, as at 8, to accommodate the introduction of a sealing filler 9 of plastic material, adapted to produce a water-tight and weather-proof joint. 15

The peripheral frame 10 of these panels 4 is precast of cement, concrete or the like, and is provided with an interior edge groove 11 to accommodate the edges of the glass 20 panel 12.

In order to best assure a tight and permanent sealing for the glass, it is set in place in the process of molding so that when the cement is set it is secured permanently in place, a strip or layer of plastic cementitious material of elastic or yielding material 13 being interposed between the glass and the frame to serve substantially as a cushioning 25 gasket to protect the glass from rupture by expansion stresses, and to render the skylight weather-proof in every respect.

In order to prevent the collection of moisture and dripping thereof from the panel, a moisture collecting trough 14 is molded in 30 the upper edge of the lower portion of the panel frame adjacent to the lower edge of the glass for collecting the moisture which condenses on the inner side of the pane and runs down thereon. A moisture outlet or 35 weep hole 15 is formed in the frame member, extending diagonally outward to discharge at the lower edge of the panel onto the next lower panel.

It is to be noted that the panels 3 and 4 40 are adapted to accommodate the staggered relation shown in Fig. 2, by reason of the vertical groove 16 on the under side at the lower edge to receive the upstanding ridge-forming joint members 7 of the next lower 45 adjacent course of panels. Moreover, for the sake of reinforcement, the wall is curved upwardly at 17 over these grooves, and in the case of the solid panels 3 this rib-like formation 17 extends nearly to the upper 50 edge.

Referring to the joint sealing material, it 55 is to be understood that for the purpose of economy, as well also as efficient sealing purposes, the inner part of the seal may consist of a relatively crude or inexpensive 60 filler, while the outer part or surface layer may be of a more refined and expensive nature, better adapted to resist the elements and prevent cracking or other deterioration.

65 Referring to the construction of the panels

4, the sealing material 13 extending around the rim of the glass, it should be noted, extends over a sufficient border zone to stand out free from the adjacent inner edge of the cement on both sides of the glass whereby 70 there is ample clearance between the cement and the glass. This is desirable in order to prevent any possibility of the cement coming in contact with or setting on the glass in the process of manufacture of these 75 panels.

It is to be understood that in the manufacture of the skylight panels herein referred to, the bottom half or inside portion of the frame is molded by pouring cement 80 into a rectangular mold having a raised center of suitable size, whereby the cement assumes a rectangular open frame-like shape. Then after applying a striker to produce the proper surface, a pane of glass 85 which has been dipped on all four sides in a yieldingly cementitious material, such as bitumen, asphalt or the like is inserted, and after covering the glass plate with a sheet of metal to protect the same from cement, and a central core block being placed on said plate, another batch of cement is poured into the mold whereby the frame is completed. The said metal plate is large enough to extend well over the inner edges of the sealing 90 material, whereby the last pouring of cement is kept away from the glass.

In order to prevent stoppage of the weep holes 15 by ice in cold weather, they are 100 formed to flare outwardly and downwardly, as shown in Fig. 5, and the interior is coated with a smooth setting material 18, preferably somewhat yielding in character, as for instance an asphalt product or paint, as shown in Fig. 10.

This lining 18 protects the cement from the setting or interlocking of an ice core therein and the consequent splitting of the concrete, and also facilitates discharge downwardly of the ice core by the expansive force of 110 freezing, whereby clogging of the passage is prevented. This action is conspicuously apparent from the fact that in practice an ice core is sometimes gradually projected for a considerable distance from the mouth 15' of 115 the duct.

Although but one specific embodiment of this invention has been herein shown and described, it will be understood that numerous details of the construction shown may be altered or omitted without departing from the spirit of this invention as defined by the following claims.

I claim:

1. In a cementitious window frame, a passageway for the discharge of moisture, said passageway being flared downwardly and outwardly and having a coating to prevent the interlocking of an ice core in said passageway. 125

2. A skylight panel comprising a cementitious frame in combination with a pane of glass set therein, said frame having a moisture collecting pocket on its inner side adjacent to the lower edge of said pane, and a drain passageway extending from said pocket, said passageway being coated internally with a coating of yielding character whereby the self discharge of ice collecting in said passageway is facilitated. ¹⁰
Signed at Chicago this 29th day of June, 1925.

LEROY BAUMGARTL.
